UNITED STATES PATENT OFFICE.

HENRY HORAN, OF EAST ORANGE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 12,478, dated September 20, 1881.

Application filed August 9, 1881. Term of patent 3½ years.

To all whom it may concern:

Be it known that I, HENRY HORAN, of East Orange, in the county of Essex and State of New Jersey, have invented a new and original 5 Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

A is a large bouquet of roses and other flowers, buds, and leaves. B is a lily-plant, with 15 flower a. The figures A and B are placed side by side between ornamental bands b and d. Above the band d is a peculiar-formed leaf, e, having projecting angular stems f f and three foil leaves and buds thereon. The stems f terminate in a fanciful scroll, g, that rises above 20 two leaves, h h, and has an ornamental pendant, i.

I claim—

1. The design for carpets, consisting of the figures A B, substantially as shown. 25
2. The design for carpets, consisting of the figures A B b d, substantially as shown.
3. The design for carpets, consisting of the figures e f g h i, substantially as shown.
4. The design for carpets, consisting of the figures A B b d e f g h i, substantially as shown. 30
